Diagram of a cross-section of a plant structure, labeled 'Fig. 4.' The diagram shows a circular cross-section with a vertical axis of symmetry. The left half of the circle is filled with diagonal hatching, while the right half is filled with horizontal hatching. A vertical line extends from the center to the top of the circle. Three labels are present: 'c' at the top right, 'i' in the middle right, and 'f' at the bottom right.

UNITED STATES PATENT OFFICE.

DAVID SPITTAL, OF CHAMBLEY BASIN, QUEBEC, CANADA.

GOLF CLUB.,

Application filed August 17, 1927, Serial No. 213,663, and in Canada August 11, 1927.

My invention relates particularly to golf clubs of the wooden type although it may be applied to the irons. The invention has for its object to provide a club which will combine the good qualities of both the steel and hickory shafts with attendant elimination of torsion while maintaining the spring of the wood shaft. A further object of my invention is to reestablish the ancient club-making industry and I do this by producing a golf club having an all-wood hickory shaft sheathed with a steel shaft from the sole of the club-head to a point slightly less than half the length of the club. Both steel and wood shaft portions are rigidly anchored at the sole of the head and are united at the upper end of the steel. In this manner the steel portion of the shaft, which has heretofore been hollow, is completely filled by the hickory shaft portion, thus eliminating the vibration so common to steel shaft clubs, and therefore eliminating cracks and breakages in the head due to the vibration.

More specifically stated the invention consists of a golf club constructed with a steel shaft portion secured rigidly to the head of the club and a hickory shaft of full length and reduced in diameter to snugly fit within and extend through the steel shaft portion and the head of the club to the sole of the latter, with means for securing the ends of the hickory and steel shaft portions in the head of the club at the sole thereof.

For full comprehension, however, of my invention reference must be had to the accompanying drawings in which similar reference characters indicate the same parts and wherein:

Figure 1 is a side elevation of a driver constructed according to my invention;

Figure 2 is a longitudinal sectional view thereof;

Figure 3 is a plan view of the sole;

Figure 4 is a transverse sectional view taken on line 4-4 Figure 2; and

Figure 5 is a plan view of the sole of the club.

The head *b* of my club may be of any preferred construction. The steel shaft portion *c* is set into the head through the neck *d* of the head and rigidly secured in place as by extending it through the head to the sole where it is anchored as will be presently described.

I prefer to make the steel shaft portion slightly less than one-half the normal length of the club. The hickory shaft portion is of full length with the usual leather grip *e*. Its lower portion *f* is reduced in diameter substantially equal to the interior diameter of the tubular steel shaft portion. This reduced portion of the hickory shaft is inserted through the steel shaft portion *c* and through the neck *d* of the head to the sole *g* thereof. A wedge *h* locks the hickory shaft and through it the steel shaft in the head at the sole and a copper rivet *i* locks the hickory and steel shaft portions together, thus effectively preventing torsion between the head and wood and steel shaft portions. Another copper rivet *j* locks the wood and steel together at the head of the steel shaft portion.

I have found that a golf club constructed according to my invention is free of torsion because of the fact that the hickory shaft is rigidly secured in the head of the club and fits snugly within the steel shaft portion without play between them while the steel shaft portion is united as at *i* to the hickory shaft. The results obtained from this construction of golf club are superior to those obtained from either steel or wood shaft clubs. Although I have referred to hickory shafts, shafts of other woods may be used without departing from the spirit of my invention.

What I claim is as follows:

In a golf club the combination with a head; of a full length hickory shaft having a handle or grip at its upper end and having its lower portion reduced in diameter forming a surrounding shoulder and extending continuously to the sole of the head; a hollow steel shaft fitting tightly on the reduced portion of the hickory shaft, and being extended through the head of the club to the sole thereof; means uniting the lower ends of the steel shaft and hickory shaft within it to the head of the club at the sole thereof and means uniting the upper end of the steel shaft to the hickory shaft with the upper end of the steel shaft in bearing relation with the surrounding shoulder on the hickory shaft.

In testimony whereof I have signed my name to this specification.

DAVID SPITTAL.
